UNITED STATES PATENT OFFICE.

AUGIE L. HANSEN, OF EVANSTON, ILLINOIS.

ACETYLENE LAMP.

Application filed October 28, 1921. Serial No. 511,080.

This invention relates to improvements in acetylene lamps, and more particularly to acetylene lamps of the portable type adapted for a great variety of uses, such as providing 5 illumination in mines by the attachment of the lamp to the caps of the miners. Lamps of this character provide for the generation of acetylene gas by the slow and continuous feeding of water into a quantity 10 of carbide, and comprise in general a water reservoir in the upper portion of the lamp body and a carbide tank container in the lower portion of the lamp body, and means for conducting the water and controlling 15 its flow into the body of the carbide.

The ordinary type of acetylene lamp is so designed as to regulate the feed of the water to the carbide in an amount sufficient to produce a quantity of gas required at 20 the burner to produce a flame of desired intensity, the force of gravity being the only means utilized for this purpose. In some instances and under certain conditions of operation, it is desirable that an excessive 25 amount of water be introduced into the carbide, as, for instance, to promote rapid gas generation as when the lamp is being started or where increased flame intensity or flame is desired.

30 The present invention contemplates, therefore, a normal gravity feed from the water reservoir to the carbide, together with a combination of elements whereby a forced method of feeding may be resorted to when 35 desired, the object of the invention being to provide a simple and efficient method of force feeding applicable to ordinary types of acetylene lamps.

40 The novel features combined in the invention are clearly disclosed in the drawings, in which

Fig. 1 is a view in side elevation of a typical acetylene lamp with a portion broken away to show the interior construction 45 thereof.

Fig. 2 is an enlarged detailed view in vertical section of the feeding stem with associated parts,

50 Fig. 3 is an enlarged view in cross-section taken on line 3-3 of Fig. 2, and

Fig. 4 is a similar view taken on line 4-4 of Fig. 2.

55 As illustrating the application of the invention, an acetylene lamp such as shown in Figure 1 consists of two main parts; namely, a cylindric body member 2 having

a chamber in its upper portion forming the water reservoir 3, and a detachable receptacle 4 having screw threaded engagement with the body of the lamp 2 forming the carbide receptacle. Mounted upon the body member 2 is a reflector 5 at the center of which is located a burner (not shown) and the gas being conducted to the burner by suitable passage communicating with the gas chamber immediately below the water reservoir 3. These details of construction are not essential to the present invention, and therefore are omitted.

Extending transversely of the body member, and forming the bottom of the water reservoir 3, is a wall 6 spaced inwardly from the open lower end of said body member, the intervening space forming the open gas chamber hereinbefore referred to. In 75 the upper wall 7 of the body member is provided a filling opening normally closed by a hinge cap 8 mounted upon a bracket 9 having suitable connection with the lamp body. A hook member 10 is also secured to 80 the lamp body, and is utilized for attaching the lamp to any desired supporting member.

Extending centrally and axially of the lamp body 2 is a cylindric tube or stem 11 passing thru the top wall 7 downwardly 85 thru the bottom wall 6 of the water receptacle 3 and terminating some distance beyond the lower end of the body member, so that its extremity occupies a position centrally 90 of the carbide tank 4 when the same is attached to the lamp body. The mounting of the stem 11 is carried out in such a way as to be watertight at the points where the same passes thru the walls of the body member, altho the interior of the stem 95 communicates with the water receptacle 3 thru the medium of a small opening 12 located just above and adjacent to the bottom wall 6 of the water receptacle. The stem 11 is open at its upper and lower ends, and is provided intermediate its ends with an internally reduced portion 13 located just below the water inlet opening 12. Mounted

100 within the upper portion of the stem 11 is a rotative sleeve valve 14 adapted to have endwise abutting engagement with the upwardly facing shoulder or seat of the reduced portion 13, and provided at its upper end with an enlarged head or threaded portion 15 having internally screw threaded engagement with the upper portion of the stem 11 and a laterally extending arm 15a in- 105 110 115

tegral with that portion of the head 15 exterior of the stem 11. The external diameter of the sleeve 14 is slightly less than the internal diameter of the stem 11 so as to provide a passageway therebetween, altho when the sleeve is in bearing engagement with the reduced portion 13, communication is cut off between the spaces above and below the same. In other words, the sleeve 10 serves as a valve member controlling the passage of water thru the inlet opening 12, and thence downwardly to the lower end of the stem 11 by rotating the sleeve in either direction to move the end thereof away 15 from or in contact with the seat forming shoulder 13 thru the medium of the screw threaded connection between said sleeve and the stem 11.

Extending axially of the stem 11 and enclosed within the sleeve 14 is a plunger rod 16 extending substantially the full length of said stem. At the upper end of the rod and located beyond the head 15 of the sleeve 14 is a head 16^a, adapted to be grasped by the 25 fingers in operating the plunger rod in a manner hereinafter to be pointed out. Continuing downwardly beyond the sleeve 14 in which the rod fits rather snugly, the same passes thru the reduced portion 13, terminating 30 in an enlarged cylindric end portion or piston 17. The lower portion of the stem 11 adjacent the piston 17 of the plunger rod is somewhat reduced in internal diameter to a size slightly greater than the diameter of 35 the piston 17, and forms a cylinder 18 co-operating with the piston in a manner hereinafter to be set forth.

The extreme lower end of the stem 11 and beyond the piston 17 is treated in the following manner: A plurality of slots 11^a extend longitudinally of the same and preferably arranged in angles of 90 degrees apart, there being preferably four of such slots as clearly shown in Fig. 3. Loosely retained in 45 the lower end of the stem 11 is a solid penetrating member 19 consisting of conical shaped head 20 provided with a reduced neck portion 21 projecting from the base of said head, said neck portion in turn having an enlarged extremity 21^a fitting within the end of the stem 11, the edges thereof being swaged or upset inwardly so as to engage or grip the reduced portion of the stem 21 intermediate the head 20 and the enlarged end portion 50 21^a as clearly shown in Fig. 2.

It is to be observed that the longitudinal opening thru the intermediate reduced portion 13 has a greater diameter than that of the rod 16 so that the water passing thru the 60 inlet opening 12 is free to pass downwardly to the lower end of the stem, providing the sleeve or valve 14 is raised sufficiently to open the passageway thru said reduced portion 13. Assuming therefore that the valve sleeve 14 is open, the water from the reser-

voir 3 flows downwardly in the same, passing around the piston 17, and thence into the carbide thru the slots 11^a. Under these conditions a normal quantity of gas will be generated. Assuming, however, that it is desired to promote the generation of gas, it being understood that the rate of gas generation is dependent upon the amount of water fed to the carbide, this increased action is accomplished by grasping the head 16^a of the plunger rod and working the same up and down with a reciprocating movement. The result of this manipulation is as follows: The water passing downwardly into the lower end of the stem momentarily accumulates in the cylinder-like portion 18 of the stem, and as the plunger rod is forced downwardly, the water thus accumulated is forced outwardly into the body of the carbide by the action of the piston 17. In this manner pressure is applied to the water, thereby promoting the gas generation by forcibly feeding the water to the carbide.

Manifestly, the feeding of the water may be regulated by the amount that the sleeve valve 14 is opened, so that the generation of gas may be regulated independently of the force feeding plunger 16. Furthermore, the amount that said sleeve valve is opened may be determined by its angular position with reference to the lamp body, the latter being preferably provided with a sector formed along the periphery of the top wall 7 by the provision of a series of knobs 22 which engage the bent or looped end 23 at the end of the lever arm 16^a. In this manner the sleeve valve can be retained in any desired position of valve opening.

The function of the penetrating member 19 is to enable the stem to be forced downwardly thru the carbide, which practically fills the tank 4, the carbide being ordinarily in the form of lumps which do not readily yield to the introduction of the stem. Furthermore, after the operation of the lamp for any length of time, the carbide becomes slaked; that is to say, it disintegrates in the form of a damp powdered mass which is inclined to clog the discharge slots 18 at the lower end of the stem. If this condition occurs, thereby interrupting the feeding of the water into the carbide, the penetrating member 19 can be grasped by the fingers, and with a gyratory motion, coupled with end-wise motion, the slaked carbide can be loosened and readily removed from the slots 18, thus freeing any obstruction that might result.

Having described a preferred embodiment of the invention and the function thereof, I claim as my invention:

In an acetylene lamp, the combination of a water receptacle, a carbide receptacle below said water receptacle, a feed tube extending from said water receptacle into said carbide

receptacle and provided with an outlet at its lower end, said tube having a cylinder-like portion of reduced diameter adjacent said outlet and a portion of increased diameter above said cylinder-like portion and communicating therewith, and a plunger-rod mounted in said tube and having a piston-like head adapted to fit within said cylinder-like por-

tion of said tube and acting to force the water through said outlet in the reciprocating movement of said rod.

In witness whereof, I hereunto subscribe my name this 22nd day of October, A. D. 1921.

AUGIE L. HANSEN.
